DESIGN FOR A GRIDDE STAND OR THE LIKE

Loyd W. Ray and Franklin H. Wirtz, Columbus,
Ohio, assignor to White Castle System, Inc.,
Columbus, Ohio, a corporation of Delaware

Application March 23, 1938, Serial No. 76,028

Term of patent 14 years

To all whom it may concern:

Be it known, that we, Loyd W. Ray and Franklin H. Wirtz, citizens of the United States, residing at Columbus, in the county of Franklin and State of Ohio, have invented a new, original, and ornamental Design for a Griddle Stand or the like, of which the following is a specification, reference being had to the accompanying drawings, forming a part thereof.

stand embodying our new design as seen from in front of the stand; and

Fig. 2 is a perspective view of Fig. 1 showing the rear of the stand.

We claim:

The ornamental design for a griddle stand or the like substantially as shown.

LOYD W. RAY.
FRANKLIN H. WIRTZ.
